US00D628639S

(12) **United States Design Patent**
Wang

(10) **Patent No.:** **US D628,639 S**
(45) **Date of Patent:** **** Dec. 7, 2010**

(54) **PEN**

(75) Inventor: **Weijie Wang**, Ningbo (CN)

(73) Assignee: **Beifa Group Co., Ltd.**, Ningbo (CN)

(**) Term: **14 Years**

(21) Appl. No.: **29/354,358**

(22) Filed: **Jan. 22, 2010**

(30) **Foreign Application Priority Data**

Jul. 22, 2009 (CN) 2009 3 0203706

(51) **LOC (9) Cl.** **19-06**

(52) **U.S. Cl.** **D19/48**

(58) **Field of Classification Search** ..... D14/411, D14/431; D19/35, 36, 41, 42, 43, 44, 45, D19/46, 47, 48, 49, 50, 51, 54, 55, 56; 24/11 F, 24/11 P, 11 R; 401/6, 52, 99, 100, 104, 105, 401/106, 107, 108, 109, 192, 195, 243, 244, 401/245, 246, 247

See application file for complete search history.

(57) **CLAIM**

The ornamental design for a pen, as shown and described.

DESCRIPTION

FIG. 1 is a front right side perspective view of a pen showing my new design;

FIG. 2 is a right side elevation view thereof, with the left side elevation view being a minor image of the right side elevation view;

FIG. 3 is a front elevation view thereof;

FIG. 4 is a rear elevation view thereof;

FIG. 5 is an enlarged top plan view thereof; and,

FIG. 6 is an enlarged bottom plan view thereof.
